UNITED STATES PATENT OFFICE.

HARRY C. LAFFERTY, OF ALLEGHENY, PENNSYLVANIA.

DUST-GUARD.

SPECIFICATION forming part of Letters Patent No. 751,306, dated February 2, 1904.

Application filed September 26, 1903. Serial No. 174,736. (No model.)

To all whom it may concern:

Be it known that I, HARRY C. LAFFERTY, a citizen of the United States of America, residing at Allegheny, in the county of Allegheny and State of Pennsylvania, have invented certain new and useful Improvements in Dust-Guards, of which the following is a specification, reference being had therein to the accompanying drawings.

10 This invention relates to certain new and useful improvements in dust-guards, and relates more particularly to that class of dust-guards employed in connection with the journal-boxes of railroad-cars to prevent dust, dirt, or other foreign substance working its way onto the journals of the axle.

15 The object of the present invention is to provide a dust-guard with a non-combustible-material spring held against the neck of the journal, so that in event of any wear in said neck the material will still be held against the same; and a further object of the invention is to simplify the construction of the frame of the guard and at the same time produce a construction capable of withstanding strains against the same.

20 Briefly described, the invention comprises a frame or casing embodying two side plates which have their side edges flanged over and 30 interlocked, each of these plates being provided with an opening with a top-piece or cap-plate slipped onto the upper ends of said two plates. Fitted between the two plates in the lower half of the casing thus formed is a sheet 35 of non-combustible material, preferably asbestos, cut out to conform to the opening in the plates and with its upper end projecting into said opening. Fitted to have vertical movement in the upper part of the casing 40 formed by the two plates is a housing which carries a sheet of non-combustible material, preferably asbestos, the lower end of which is cut out to receive the journal and which lower end projects beyond the lower end of 45 the housing, so as to engage directly with the journal. Fitted between the upper end of the housing and the cap-plate is a spring which serves to hold the material carried by the housing normally in engagement with the 50 journal.

All of the above construction will be hereinafter more specifically described, and then particularly pointed out in the claims, and in describing the invention in detail reference will be had to the accompanying drawings, 55 forming a part of this application, and wherein like numerals of reference will be employed for indicating like parts throughout the different views of the drawings, in which—

Figure 1 is a transverse vertical sectional view of the dust-guard in position in the journal-box, the latter and also a part of the car-wheel being shown. Fig. 2 is a detached front elevation of the guard. Fig. 3 is a similar rear elevation. Fig. 4 is an edge view. 60 Fig. 5 is a transverse vertical sectional view. Fig. 6 is a horizontal sectional view. Fig. 7 is a detached detail perspective view of the movable housing. Fig. 8 is a like view of the non-combustible sheet carried by said 70 housing, and Fig. 9 is a similar view of the non-combustible sheet that is adapted to be secured in the lower half of the casing.

To put my invention into practice, I provide a front plate 1, of suitable sheet metal, 75 and a rear plate 2, of the same material, which latter plate has its side edges turned at right angles to the plate to form the sides 3, the free edges of said sides being turned over to 80 form the channels with which the turned-over edges of the plate 1 are interlocked, the turned-over side edges 5 of the front plate being slid into engagement with the turned-over edges 4 of the sides 3. The plates are provided with registering openings 6 to receive the axle 8, as seen in Fig. 1, and the casing is closed at its lower end by a bottom 7, formed by the bent-over lower end of the rear plate 2, with the lower end of front plate 1 flanged over on said bottom, as shown at 9. 90 Combined stiffening-straps and wearing-plates 10 may be employed on the faces of the plates, which in practice are riveted only to the plate to which they are attached. I also preferably provide a strap 11, attached to one face 95 of the casing, at the upper end thereof, by means of which the guard may be readily withdrawn from the journal-box 12. In the lower half of the guard is placed a sheet of non-combustible material 14, preferably composed 100

of asbestos, as this material has been found in practice to be the more satisfactory, held rigid in the lower half of the casing by cement and a pair of rivets 15, passed through from 5 opposite sides of the casing and riveted. This asbestos sheet in its upper end is cut away, as at 16, to receive the journal of the axle, and the sheet when first placed in position is of a size sufficient to have its upper end project 10 into the opening 6 in order to allow for considerable wear of the asbestos sheet before the journal would engage with the walls of the opening 6. In the upper half of the casing is mounted for vertical movement a housing 17, cut away, as at 18, to receive the journal of the axle and in which is rigidly secured by cementing and by riveting or otherwise a non-combustible sheet 19, preferably of asbestos, this sheet 19 having the cut-away portion 15 15 conforming to the cut-away portion of its housing. Like the sheet 14, this sheet 19 is made of sufficient size so that its lower end will protrude or project beyond the lower end of the housing 17 and upper half of the wall of the opening 6, whereby to engage directly with 20 the journal of the axle. The asbestos sheet carried by this housing is held at all times in engagement with the journal of the axle by means of a spring 21, the bow of which bears 25 against the upper end of the housing and the ends of which engage the upper end of the housing and the ends of which engage the cap-plate 22. This cap-plate 22 is secured in position by crimping over the edges or upper 30 end of plates 1 and 2 and likewise crimping or flanging over the edges of the cap-plate 22, as seen in Figs. 4 and 5, the cap-plate being slid into position, and after being positioned the ends 23 of this plate are turned down to 35 retain same.

The projection of the edge or ends of the asbestos sheets into the opening in the plates permits same to engage directly with the journal of the axle and permits of the same being 40 worn to a considerable extent before the journal will engage with the plates. Any movement imparted to the journal will tend to raise the upper asbestos plate, the same remaining during such movement in engagement with 45 the journal. The housing 17 is of a size which will permit of a lateral movement of 50

the journal, as well as a vertical movement to raise the housing.

Having fully described my invention, what I claim as new, and desire to secure by Letters 55 Patent, is—

1. A dust-guard comprising side plates formed with openings, a sheet of non-combustible material mounted between the plates at the lower ends thereof and occupying the 60 entire space therebetween and having a central opening, said material projecting into the plate-openings, a housing having a cut-away portion, with non-combustible material clamped between the sides of the housing, 65 means for securing the non-combustible materials to the housing and to the said side plates, a cap-plate at the upper end of the side plates with a spring bearing thereagainst and against the upper end of the housing, said cap- 70 plate having inturned side flanges for engagement with the outturned flanges at the upper end of the side plates, the ends of the cap-plate being bent downwardly to engage the side of the side plates and prevent lateral 75 movement to the cap-plate.

2. A dust-guard comprising metal side plates each provided with an opening, a sheet of non-combustible material occupying the entire space between the said plates at the 80 lower ends thereof and having a portion extending within the openings thereof, means for securing the material between the plates, a housing formed of sheet metal doubled over intermediate its ends and provided with a 85 semicircular aperture at its free ends, the sides of said housing being open, a sheet of non-combustible material secured between the ends of the housing, said material projecting into the semicircular aperture of the said ends, 90 a cap-plate mounted on the upper ends of the side plates, and having its ends bent downwardly to engage the sides of the side plates when in its normal position and a spring interposed between the end of the housing and 95 said cap-plate.

In testimony whereof I affix my signature in the presence of two witnesses.

HARRY C. LAFFERTY.
